UNITED STATES PATENT OFFICE.

JACOB EMIL SCHMANDT, OF EDDYVILLE, OREGON.

BAG SUPPORTING AND CLAMPING MECHANISM.

1,346,260.

Specification of Letters Patent. Patented July 13, 1920.

Original application filed November 23, 1918, Serial No. 263,858. Divided and this application filed August 22, 1919. Serial No. 319,161.

To all whom it may concern:

Be it known that I, JACOB EMIL SCHMANDT, a citizen of the United States, residing at Eddyville, in the county of Lincoln and State of Oregon, have invented certain new and useful Improvements in Bag Supporting and Clamping Mechanism, of which the following is a specification.

This invention relates to bag or sack holders, and particularly to a bag or sack holder peculiarly designed for use in connection with the bag sewing mechanism forming the subject matter of my application, filed November 23, 1918, Serial No. 263,858, of which application the present application is a division. The bag sewing mechanism illustrated in my aforesaid application is designed to sew up the mouth of a bag after the latter is filled with grain.

The general object of this present invention is to provide means whereby the mouth of a bag may be held in an open position and the mouth of the bag distended, and whereby the clamping members which engage the mouth of the bag may be shifted toward each other to carry the two margins of the bag mouth together so as to permit the sewing mechanism to pass across the mouth of a bag and sew these two margins of the bag together.

A further object is to provide improved means for firmly engaging the mouth of the bag including clamping members engageable on each side of a thickness of fabric.

And a further object is to provide a bag mouth clamping means consisting of a plurality of pivoted sections which will firmly engage all portions of the bag, and whereby the bag may be distended or closed.

Other objects will appear in the course of the following description.

My invention is illustrated in the accompanying drawings, wherein:—

Figure 1 is a front elevation of a bag holder constructed in accordance with my invention;

Fig. 2 is a side elevation thereof;

Fig. 3 is a top plan view thereof;

Fig. 4 is a perspective view of the members 12 and 15;

Fig. 5 is a sectional view of the slides 12 and the rails 6 supporting the slides, and the means for operating said slides;

Fig. 6 is a fragmentary perspective view of the members 6, 7 and 8;

Fig. 7 is a top plan view of the bag clamps in their closed position;

Fig. 8 is a top plan view of the bag clamps in their opened or expanded position;

Fig. 9 is a section on the line 9—9 of Fig. 7;

Fig. 10 is a side elevation of the bag clamping jaws;

Fig. 11 is a top plan view of the bag clamping jaws in their closed position;

Fig. 12 is a section on the line 12—12 of Fig. 11.

Referring to the drawings, it will be seen that the bag holder comprises two similar, vertically disposed, triangular frames which may be mounted and secured in any suitable manner upon the discharge end of a threshing machine, each of these frames consisting of a vertically disposed member 5, horizontally disposed, outwardly projecting rails 6, and upwardly inclined supporting braces 7. The rails 6 are connected by a transversely extending, horizontal angle iron 8 which is secured to the rails by means of the bracket plates 9. The angle iron 8 extends beneath the lower horizontal rails 6 and projects laterally some distance therefrom in order to support the sewing mechanism or the sewing machine which, however, is not illustrated in the present application.

Horizontal, inwardly projecting track bars 10 are disposed parallel to the rails 6 and supported thereby in any suitable manner, the outer ends of these track bars being connected to the horizontal flange of the angle iron 8. The inner ends of the track bars are connected by means of a bar 11. Slidably mounted upon these track bars 10 are slide bars 12 which are slidably engaged with the tracks 10 in any suitable manner and are supported thereby, these slide bars 12 being spaced at their inner ends by a transverse bar 13. The outer ends of the bars 12 carry depending bracket plates 14 secured to the vertical flange of an angle iron 15. The angle iron 15 and the angle iron 8 coact with each other to support the bag holding device, as will presently appear.

For the purpose of oscillating the slide bars 12 and the connected angle iron 15, a transverse shaft 16 is mounted in suitable bearings on the members 6 and carries the crank arms 17. These crank arms are pivotally connected to connecting rods 18 which, at their outer ends, are pivoted, at 19, to the

slide bars 12. The shaft 16 is provided with a crank 20 whereby the shaft may be oscillated, and each of the rods 18 is bowed intermediate its ends, as shown at 21, to permit 5 the crank shafts 17 to be shifted to the dotted line position in Fig. 5, with the connecting rods 18 lying flat upon the slide bars 12, in other words these bowed portions 21 accommodate the shaft 16. It will be ob- 10 vious that by rotating the shaft 16 through the medium of the crank 20, that the angle iron 15 will be shifted toward the angle iron 8 or away from the angle iron 8.

Carried upon these angle irons 8 and 15 is 15 a bag mouth clamping or gripping device which is now to be described. Referring to Figs. 7 to 12 inclusive of the drawings, it will be seen that the sack supporting or gripping device includes a pair of longitudinal 20 side plates 22 which are hingedly connected at their ends, as at 23, to end plates 24. The plates 24 at corresponding ends of the side plates 22 are hingedly connected to each other, as at 25. Each of these plates is 25 formed along its lower longitudinal edge with outwardly projecting teeth 26. Outer, longitudinal, side plates 27 are hingedly connected to the upper edges of the inner plates 22, as at 28, and to these outer side plates, 30 the outer end plates 30 are hinged, as indicated at 29, said plates 30 being hinged to the corresponding inner end plates 24, as at 31. The inner ends of the outer plates 30 are 35 spaced from each other, as clearly seen in Fig. 9. The outer side plates 27 are each provided with flanges 32 projecting outwardly from the upper edge of the side plate in spaced relation to the opposite ends of the plate. These plates 27 are also centrally 40 formed with the upwardly projecting, outwardly inclined wings 33, to which handle rods 34 are riveted at their extremities. The plates 27 at the juncture of the wings 33 therewith, are connected to the inner side plates 28 by means of the spring hinges 35. The inner plates 22 are also centrally formed 45 with upwardly projecting wings or flanges 36 in opposed relation to the wings 33. The outer plates 27 and 30 are provided upon 50 their lower edges with spaced teeth, as shown at 37, which are alternately disposed with relation to the teeth 26 on the inner plates and project toward the same.

In the use of the sack gripping device, the 55 upper edges of the sack are adapted to be engaged between the inner and outer series of plates or jaws, the handles 34 being forced toward each other so that the outer series of plates are moved outwardly into angular 60 spaced relation to the inner plates, as shown in Fig. 9. The handle members are then released so that the spring hinges 35 force the outer series of plates inwardly to their normal positions. Thus, the teeth 26 and 37 65 on the lower edges of the two series of plates

engaging in the opposite sides of the walls of the sack will securely grip and hold the same. The sack is then disposed in position between the angle bars 8 and 15 with the flanges 32 resting upon the upstanding 70 flanges of said bars. Thus, the mouth of the sack is held in a wide open position while the grain or other material is fed into the same (see Fig. 3). After the sack has been filled, the crank 20 is actuated as above explained. The outer angle bar 15 is thus moved inwardly and the pressure of the same against the sack gripping and supporting device, collapses said device, the ends thereof folding inwardly toward each other, 80 as seen in Fig. 7, until the mouth of the sack is securely closed. The opposed walls of the sack are now stitched or sewed together at a point immediately below the clamping or gripping device. 85

The mechanism for sewing the opposed walls of the sack together is fully described and illustrated in my co-pending application above referred to and, therefore, does not require any description at this place, but 90 it may be said that the sewing machine is mounted upon a lateral extension of the angle iron 8 and is designed to be shifted laterally away from the bag supporting frame when the bag is being filled and until the bag 95 clamping members are brought together, and that when the angle irons 15 and 8 are moved into proximity with each other and the bag clamping means is collapsed, then the sewing machine is shifted transversely 100 of the bag supporting frame and the closed mouth of the bag is stitched. After the bag has been sewed and the sewing mechanism has been retracted, it is shifted laterally beyond the bag supporting frame and then the 105 handles 34 are drawn together to release the bag. The crank handle 20 is then actuated to carry the angle iron 15 outward and to expand the bag clamping or gripping device or a new bag may be inserted with the 110 gripping device partly expanded and then the crank handle 20 actuated to fully expand the mouth of the bag and hold it distended ready for the reception of grain.

My clamping device is such that the 115 mouth of the bag is held fully open at the time it is receiving grain, while the edge of the fabric forming the bag is clamped entirely around the mouth of the bag so that there is no danger of the bag becoming detached at any point from the distending device. The fabric is clamped so firmly between the jaws 22 and 27 and 31 and 24 that the mouth of the bag will be positively engaged and the wall of the bag collapsed or 120 distended by the action of crank 20.

While I have illustrated and described a form of my invention which I believe to be thoroughly effective in practice, yet I do not wish to be limited to this, as it is obvious 130

that many changes might be made in the details of construction and arrangement of parts without departing from the spirit of the invention.

5 I claim:

1. In combination, fixed and movable bag supporting bars, manually operable means for shifting the movable supporting bar toward the fixed bar to close the mouth of the bag, said means including a rotatable shaft, spaced rods pivotally connected at one of their ends to the movable bar, and means connecting the other ends of said rods to the shaft, whereby said bar is moved to its 15 effective clamping position upon a partial rotation of the shaft.

2. In combination, fixed and movable bag supporting bars, manually operable means for shifting the movable supporting bar toward the fixed bar to close the mouth of the bag, said means including a rotatable shaft, spaced rods pivotally connected at one of their ends to the movable bar, and link members fixed at one of their ends to the shaft 20 and operatively connected at their other ends to the respective rods to move said supporting bar relative to the fixed bar to support the bag with the mouth thereof open or to close the mouth of the bag upon a partial rotation of said shaft.

3. In combination, fixed and movable bag supporting bars, manually operable means for shifting the movable supporting bar toward the fixed bar to close the mouth of a bag disposed between said bars, opposed sets of collapsible and expansible bag mouth gripping means carried upon said bars and each set including a middle section and end sections hinged to the middle section, each 35 of said sections having inner and outer jaws, one of the jaws being fixed and the other being movable and resiliently urged toward the other jaw, between which the margin of fabric at the mouth of the bag may be 40 clamped, the end sections of the two sets of mouth gripping means being hinged to each other, and means whereby the movable jaws of all of the sections of the two sets may be simultaneously opened or closed.

4. A bag holding device including hingedly connected side and end plates adapted to be arranged in extended relation within the mouth of a bag to hold the same open, additional side and end plates hingedly connected to the corresponding first named plates for movement relative thereto, one pair of the latter end plates being hingedly connected to one of the latter side plates and movable independently of the other side and end plates and constituting a clamping jaw for engagement upon the exterior of the bag wall, means normally urging the clamping jaws to closed position, and handle members fixed to each of the latter slide plates for 60 opening the jaws.

5. A bag holding device comprising a series of outer jaw members hinged to each other, an opposite series of inner jaw members hinged to each other, a series of outer jaw members disposed outward of the first 70 and second named series of jaw members, the outer jaw members of each series being hinged to each other, springs connecting each series of outer jaw members to the adjacent series of inner jaw members and 75 urging said jaw members toward each other, manually operable means for opening said jaw members to release a bag, and means for causing one series of jaw members to operate each other and thereby shift the 80 two series of jaw members into parallel relation or shift the jaw members in relative directions opposite to each other to thereby expand the bag holding devices.

6. A bag holding device comprising oppositely disposed side inner jaw members designed to engage the opposite middle portions of the mouth of a bag, end inner jaw members hinged to the extremities of the side jaw members for movement in the same 90 plane as the inner jaw members, said end inner jaw members at opposite ends of the bag holding device being hinged to each other, oppositely disposed outer side jaw members extending parallel to the inner side 95 jaw members, end outer jaw members hinged to the outer side jaw members for movement in the same plane therat, the outer jaw members on one side being pivotally connected to the inner jaw members on the 100 same side for movement toward and from the inner jaw members, and springs urging the inner and outer jaw members toward each other.

7. A bag holding device comprising oppositely disposed side inner jaw members designed to engage the oppositely middle portions of the mouth of a bag, end inner jaw members hinged to the extremities of the side jaw members for movement in the same 105 plane as the inner jaw member, said end inner jaw members at opposite ends of the bag holding device being hinged to each other, oppositely disposed outer side jaw members extending parallel to the inner side 110 jaw members, end outer jaw members hinged to the outer side jaw members for movement in the same plane therat, the outer jaw members on one side being pivotally connected to the inner jaw members on the 115 same side for movement toward and from the inner jaw members, springs urging the inner and outer jaw members toward each other, and handle members attached to the middle portions of the outer 120 side jaw members.

8. A bag holding device including oppositely disposed middle bag-clamping devices, oppositely disposed end bag-clamping devices, each of said clamping devices having an 125 130

outer and inner jaw, the jaws being resiliently urged toward each other, the bag-clamping devices being hingedly connected to each other for movement toward or from each other in the same plane, and means disposed on the oppositely disposed middle bag-clamping devices whereby the jaws may be separated against the action of said springs, said means causing the separation of the middle bag clamping devices and of the end bag clamping devices.

9. In a bag supporting mechanism, fixed and movable bag supporting bars, manually

operable means for shifting the movable supporting bars toward or from the fixed bar to close or open the mouth of the bag, and a bag holder comprising bag gripping jaws formed in sections, the sections being hinged to each other whereby the sections may be expanded or closed into a parallel relation, certain of said sections being provided with oppositely disposed flanges adapted to rest on and be supported by said jaws.

In testimony whereof I affix my signature.

JACOB EMIL SCHMANDT.
